UNITED STATES PATENT OFFICE

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WEFT DETECTING MECHANISM FOR LOOM SHUTTLES

Application filed January 18, 1932. Serial No. 587,233.

This invention relates to weft detecting mechanism which is electrically operated and which is mounted in and movable with a shuttle. Such detecting mechanisms have been heretofore manufactured, in which a detecting member was mounted in the shuttle spindle and was held in position to prevent contact in an electric circuit so long as a sufficient supply of weft remained on the bobbin in the shuttle. When the weft was substantially exhausted, the detecting member was released, and moved to a position to complete the circuit and give a replenishing indication.

This prior mechanism has been found to be somewhat unreliable in closing the circuit after release by the detecting member, and it is the general object of my present invention to provide improved contact-making devices for use in weft detecting mechanism of the general type above described, which devices are so designed as to be reliable and satisfactory for their intended purposes.

I further provide a construction in which the contact members are distinct and separate from the detecting member. This permits non-conducting material to be used for the detecting member if so desired and has other distinct advantages.

My invention further relates to arrangements and combinations of parts which will be hereinafter described and more particularly pointed out in the appended claims.

Two forms of the invention are shown in the drawing, in which

Fig. 1 is a sectional side elevation of a shuttle embodying one form of my improved construction;

Fig. 2 is a plan view, looking in the direction of the arrow 2 in Fig. 1;

Fig. 3 is a view similar to Fig. 1 but showing the parts in a different position;

Fig. 4 is a detail sectional end elevation, taken along the line 4—4 in Fig. 2;

Fig. 5 is a detail perspective view of certain contact and terminal parts;

Fig. 6 is a partial sectional side elevation of a shuttle embodying a second form of my invention, and

Fig. 7 is a plan view, looking in the direction of the arrow 7 in Fig. 6.

Referring particularly to Figs. 1 to 5, I have shown a shuttle S having a spindle 10 mounted to swing about a stud or screw 11 extending transversely through the shuttle body. The spindle as shown herein is formed with the base portion in two parts, spaced to provide a longitudinal recess 12 in which a weft detecting member 13 is mounted.

The member 13 is also pivoted on the stud or screw 11 and may be provided with an insulating bushing 14, unless the detecting member is formed of fibre or other non-conducting material.

An enlarged end portion 16 of the member 13 extends out through a slot 18 in a bobbin B mounted on the spindle 10 and engages the inside of the weft W on the bobbin B.

A relatively heavy spring 20 is mounted in a recess in the shuttle body and engages one or the other of two flat surfaces 21 and 22 on the pivoted end of the spindle 10. The spindle is movable manually from the position shown in Fig. 1 to that shown in Fig. 3, and will be held yieldingly in either position by the spring 20.

The detecting member 13 is provided with a lug 30 projecting rearwardly beyond the axis of the detecting member and normally engaging the under side of a contact plate 31, pivoted on a cross stud 32, preferably fixed in a metallic casing 33 (Figs 2 and 3). A rubber cord or tension member 35 is secured at one end to the contact plate 31 and at the other end to a screw 36 by which the tension of the cord may be adjusted.

Contact plates 40 and 41 are mounted in one side face of the shuttle S and are connected by wires 42 and 43 (Fig. 5) to terminals 44 and 45, which terminals are formed as rings or clamps secured in spaced relation on an insulating bushing 46, supported by a cross-pin or stud 47. The contact plate 31 overlies the terminals or rings 44 and 45 but is normally lifted therefrom by the lug 30 as shown in Fig. 1, when the bobbin B contains a sufficient supply of weft W.

When the weft is substantially exhausted, the end 16 of the detecting member 13 moves

outward through the slot 18 and the lug 30 moves downward, allowing the elastic cord 35 to move the contact plate 31 firmly into engagement with the terminal rings 44 and 45. The contact plate, being formed of conducting material, completed the circuit between the plates 41 and 42 which are mounted in the side of the shuttle. An indication of weft exhaustion is thus given through electrical connections, not shown.

When the spindle 10 is swung manually upward for replacement of the bobbin, the lug 30 swings downward away from the contact plate 31 and thus avoids injury thereto.

With this construction, the terminals 44 and 45 and contact plate 31 may be made of brass or bronze or any other suitable conducting material, and a firm and reliable contact is assured. Preferably, the contact member 31 is partially slotted, as indicated at 49 (Fig. 2) to provide resilient tongues engaging the terminals 44 and 45 respectively. Effective contact with both of the terminals is thus insured.

In the construction shown in Figs. 6 and 7, the terminal plate 41 is connected through the stud 11, casing 33 and pivot-pin 50 to a contact plate 51, while the terminal plate 40 is connected through a wire 53 to a terminal stud 55, mounted in a plate 56 of rubber or other non-conducting material. The contact plate 51 is provided with a single resilient tongue 57 for engagement with the stud 55.

Otherwise the construction is substantially as previously described, with the conducting member 13 holding the plate 51 away from the stud 55 when sufficient weft is present on the bobbin, and allowing the plate 51 to contact with the stud 55 when the weft is substantially exhausted, as indicated in Fig. 6. Tension is supplied by a rubber cord 60 having an adjusting screw 61 as previously described.

As the plate 51 is grounded on the casing 33, it is not necessary in this case to form the detecting member 13 of non-conducting material or to insulate the member 13 from the stud 11.

Both forms of my invention possess the advantage of simple and reliable construction and may be depended upon to effectively close the circuit upon substantial exhaustion of weft upon the bobbin in the shuttle.

Having thus described my invention and the advantages thereof, I do not wish to be limited to the details herein disclosed, otherwise than as set forth in the claims, but what I claim is:

1. In a loom shuttle, a pivoted shuttle spindle, a detecting member mounted to swing with said spindle and also having limited swinging movement about the axis of said spindle and relative to said spindle, a terminal fixed in said shuttle, a movable contact member engaging said terminal when

in operative position and completing a circuit therethrough, and yielding means to move said contact member to operative position, said detecting member having a portion engaging said contact member and holding said contact member in inoperative position so long as said detecting member is engaged by a sufficient supply of weft on the bobbin on the shuttle spindle.

2. The combination in a loom as set forth in claim 1, in which the detecting member has a lug normally engaging the movable contact member but movable away from said contact member when the bobbin spindle is swung upward to open the shuttle.

3. The combination in a loom as set forth in claim 1, in which the detecting member has a lug normally engaging the movable contact member, and in which said lug and detecting member are displaced in said spindle by said contact member as the latter is moved yieldingly to circuit-closing position upon substantial weft exhaustion.

4. The combination in a loom as set forth in claim 1, in which two terminals are provided and in which the contact member is normally separated from both terminals by said detecting member but engages both terminals upon substantial weft exhaustion.

5. The combination in a loom as set forth in claim 1, in which two terminals are provided and in which the movable contact member is provided with resilient portions engaging said two terminals upon indication of substantial weft exhaustion.

6. The combination in a loom as set forth in claim 1, in which said contact member is mounted to swing in said shuttle, and in which a yielding tension device is provided for said contact member, together with means for adjusting the tension thereof.

7. The combination in a loom as set forth in claim 1, in which said contact member is mounted to swing in said shuttle, and in which a rubber cord is attached at one end to said contact member, and in which means is provided for securing the other end of said cord in said shuttle and for adjusting the tension thereof.

In testimony whereof I have hereunto affixed my signature.

ELBRIDGE R. HOLMES.
